UNITED STATES PATENT OFFICE.

EDMUND B. LA SALLE, OF BATAVIA, ILLINOIS, ASSIGNOR TO UNITED STATES WIND ENGINE AND PUMP COMPANY, OF BATAVIA, ILLINOIS, A CORPORATION OF ILLINOIS.

FLOAT VALVE.

Application filed March 24, 1919. Serial No. 284,586.

To all whom it may concern:

Be it known that I, EDMUND B. LA SALLE, a citizen of the United States, residing at Batavia, in the county of Kane and State of Illinois, have invented new and useful Improvements in Float Valves, of which the following is a full, clear, concise, and exact description, reference being had to the accompanying drawing, forming a part of this specification.

My invention relates to improvements in float valves, of the type designed especially for use in connection with water tanks to control inlet to and outlet from the tank.

The object of my invention is the production of a device of this character which will be of durable and economical construction, one which may be readily and expeditiously taken apart to renew or repair a disabled part of the valve, one which will positively prevent overflowing of the tank and one which will be highly efficient in operation. Other objects will appear hereinafter.

With these objects in view, the invention consists in the combinations and arrangements of parts hereinafter described and claimed.

The invention will be best understood by reference to the accompanying drawings forming a part of this specification, and in which—

Fig. 1 is a partially diagrammatic view of a water tank and associated piping and elements, in connection with which is arranged a float valve embodying the invention;

Fig. 2 is an axial section through the float valve detached;

Fig. 3 a section taken on substantially line 3—3 of Fig. 2; and

Fig. 4 a section taken on substantially line 4—4 of Fig. 2.

The preferred form of construction as illustrated in the drawings, is shown applied to a tank or reservoir 5 with the bottom of which communicates a pipe 6 adapted to serve the double function of an inlet pipe and a discharge pipe. Provided for cooperation with the pipe 6, is a pump 7 of any ordinary or preferred design, through the medium of which water may be pumped through said pipe into the tank 5.

Adjacent the lower end of pipe 6 is a suitable relief valve 8 adapted to yield under a predetermined pressure to permit of drain from pipe 6. Also communicating

with the pipe 6, is an outlet faucet 9 through which, in the use of the construction, water may be drawn from the pipe 6.

Arranged in the tank 5 to control inlet to and outlet from the same is a float valve which is arranged in communication with the upper end of pipe 6. Said valve comprises a body or housing having a lower part 10 provided with a flanged base 11 with which cooperates a companion flange 11' whereby said member 10 may be securely fastened in position. Above the housing part 10 is arranged an upper housing part 12 in the form of a cap, the arrangement being such that a chamber 13 is formed within the parts 10 and 12, the lower end of which chamber communicates with the upper end of pipe 6.

Provided at the lower edge of the housing part 12 is an annular flange 14 which is adapted to register with an annular flange 15 on the upper edge of part 10 and be secured thereto by bolts or other suitable fastening devices 16. Between the flanges 14 and 15 is provided a suitable leather packing 17 which insures against any leakage through the joint.

Formed in the housing part 10 adjacent the upper edge thereof is an annular inlet port 18, the same being traversed at intervals by webbing which connects the body of member 10 with the flanged portion 15 thereof as clearly seen in Figures 2 and 4. Formed in the top of housing part 12 is an annular outlet port 19 which is also traversed at intervals by webbing which connects the portions of said housing part separated by said outlet port.

Passage through the inlet port 18 is controlled by a tubular valve or plunger 20 which is slidably mounted within the valve housing, the same being carried at the lower end of a stem 21 in threaded connection at its lower end with the spider formed within said valve. Said valve passes loosely through an opening 22 formed within the flange 15, the lower edge thereof being adapted to engage with an annular rubber valve seat 23 arranged in an annular recess 24 formed for the reception thereof in the housing part 10. The seat 23 is held in operative position by means of a clamping ring 25 of angular form in cross section which engages over the upper edge of said

valve seat, said clamping ring being held in operative relation with said valve seat, by means of a nut 26 and cooperating bolt 27 which passes through a spider formed, as seen, within said clamping ring. The lower end of said bolt is anchored in a stationary spider 28 formed within the housing part 10, the arrangement being such that the clamping ring 25 may be forced into clamping engagement with the valve seat 23 by simply tightening the nut 26. The opening 22 is of greater diameter than said clamping ring so that in the event of renewal of the valve seat, it is only necessary to detach the upper housing part 12 carrying the valve 20 therewith, whereupon the clamping ring may be released and removed, together with the resilient valve seat 23, through the opening 22. This arrangement is exceptionally convenient, permitting of renewal of the valve seat 23 with the greatest ease and expedition.

The upper end of the valve stem 21 projects exteriorly, a suitable packing or stuffing box 29 being provided to prevent leakage around said stem. Threaded upon the upper end of said valve stem is a bifurcated end piece 30 to which is pivotally connected a lever 31 fulcrumed at 32 upon the upper end of a link 33 pivotally connected at its lower end as at 34 to the housing part 12. Upon the outer end of lever 31 is adjustably mounted a weight 35 adapted normally, as will be seen, to hold the valve 20 in elevated or open position. Cooperating with said lever 31 is also a float 36 connected therewith by means of a cord, rope or other suitable connecting element 37. The said float serves, of course, to effect automatic closing of the valve 20 when the level of the water in the tank reaches a predetermined point.

For the control of the outlet port 19 is provided a circular valve 38 which is freely movable upon the valve stem 21. Upon the upper side of valve 38 is provided a rubber disk 39 secured thereto by means of a metallic clamping ring 40 with which cooperates screws 41 having threaded connection with said valve 38.

At the inner end of the port 19 are provided concentric annular valve seats 42 and 43, said port being positioned between said valve seats. The arrangement is such that, when the valve 38 is at its upper terminal of movement, the rubber disk 39 will engage simultaneously with the seats 42 and 43 thereby effectually preventing any leakage through the port 19. The valve seat 43, as will be seen, serves to guard against leakage which might otherwise occur around the valve stem 21. A helical compression spring 44 is provided to hold the valve 38 in closed position if such is found desirable in the operation of the valve as hereinafter more fully set forth.

To prevent leakage from the housing chamber 13 through the opening 22 when the valve 20 is in closed position, the packing 17 is formed at its inner edge, as at 17', into tubular or cylindrical form which closely embraces the valve 20 as clearly seen in Figure 2. In order to hold the inner portion of packing member 17 in operative position, the upper housing part 12 is formed at its inner surface with a plurality of spaced longitudinally extending ribs 45, the lower ends of which engage with said packing member to prevent the upward pressure of the water on the inside of the tank from lifting the packing and thus leaking therethrough.

The spaces between the ribs 45 permit the water pressure on the inside of the valve housing to act on the vertical or tubular portion of the packing 17, thereby holding it in close contact with the valve 20 to prevent any leakage from the inside of the valve housing to the inside of the tank.

In the operation of the device, when filling the tank, the water forced up through the pipe 6 by the pump 7 will pass into the valve housing, and thence out through the port 18 into the tank, the valve 20 being normally held in open position by the weight 35. The water will continue to flow into the tank until the predetermined level therein is reached, whereupon the float 36 will act to automatically move the valve 20 to closed position. When this takes place, it will be seen that any water which thereafter is forced into the valve will pass upwardly through the valve member 20 and impinge against the under side of valve member 38, the pressure thus exerted upon the latter serving to lift the same and press it firmly against the valve seats 42 and 43, thereby closing the outlet port 19. With both the inlet and outlet ports 18 and 19 closed, overflowing of the tank will be positively prevented, and any further discharge of water into the pipe 6 by the pump 7 will cause an increased pressure therein, which will open the relief valve 8, thus serving to notify the operator or attendant of the pump that the tank is filled, whereupon the pump will be shut off. Hence, with the arrangement set forth, it will be seen that continued operation of the pump, after filling of the tank, will serve only to discharge water through the relief valve, insuring against overflow of the tank.

With the tank thus filled, withdrawal therefrom may be effected by simply opening any of the discharge faucets which may be connected with the pipe 6. When this takes place, it will be seen that the pressure in the pipe 6 is reduced, thus permitting the valve 38 to automatically open by reason of the unbalanced pressures on the opposite sides thereof.

In the event that the pressure of the inflowing water is not sufficient to raise the valve 38 to closed position, as above described, a helical compression spring 44 may be provided to assist in this regard.

While I have illustrated and described the preferred form of construction for carrying my invention into effect, it is capable of modification without departing from the 10 spirit of the invention. I therefore do not wish to be limited to the precise details of construction set forth, but desire to avail myself of such variations and modifications as come within the scope of the appended 15 claims.

Having thus described my invention, what I claim as new and desire to secure by Letters Patent is:

1. The combination with a chamber having an opening, of a single unitary element for controlling inlet to and outlet from said chamber, said element comprising a body having a compartment therein communicating with said opening and having 20 inlet and outlet ports for establishing communication between said chamber and said compartment; a normally open tubular valve arranged to control said inlet port; a float for closing said valve; and a second 25 valve arranged to control said outlet port, said second valve being arranged beyond the first mentioned valve whereby the outlet flow through said outlet port is required to pass through said tubular valve.

2. The combination with a chamber having an opening, of a single unitary element for controlling inlet to and outlet from said chamber, said element comprising a body having a compartment therein communicating 30 with said opening and having inlet and outlet ports for establishing communication between said chamber and said compartment; a normally open tubular valve arranged to control said inlet port; a float 35 for closing said valve; and a second valve arranged to control said outlet port, said second valve being arranged beyond the first mentioned valve whereby the outlet flow through said outlet port is required 40 to pass through said tubular valve, said second valve being arranged in alignment with the passage through said tubular valve whereby inward flow through said passage 45 impinges against said second valve to automatically close the same.

3. The combination with a chamber, of a single unitary element for controlling inlet to and outlet from said chamber, said element comprising a body having a compartment therein communicating with said opening and having inlet and outlet ports for establishing communication between said chamber and said compartment; a normally open tubular valve arranged to control 50 said inlet port; a float for closing said

valve; a second valve arranged to control said outlet port, said second valve being arranged beyond the first mentioned valve whereby the outlet flow through said outlet port is required to pass through said tubular valve, said second valve being arranged in alignment through the passage to said tubular valve whereby inward flow through said passage impinges against said second valve to automatically close the same; and 70 a rod for operating said first valve, said second valve being slidably mounted on said rod.

4. A device of the class described comprising a body having upper and lower detachably connected parts; a packing arranged between said parts; a valve slidably mounted in said body for cooperation with a port provided in said body; and a seat for said valve in one of said parts, there being an opening 80 through which the said valve passes, said packing engaging with said valve to prevent leakage through said opening to said port.

5. A combination float valve and check valve construction for controlling the flow 90 of water to and from a tank, comprising a float valve for controlling the flow of water to the tank, and a check valve for controlling the flow of water from the tank, said float valve 95 having a stem extending through said check valve.

6. A combination float valve and check valve construction for controlling the flow of water to and from a tank, comprising a float valve for controlling the flow of water to the 100 tank, and a check valve for controlling the flow of water from the tank, said float valve having a water passage therethrough controlled by said check valve.

7. A combination float valve and check 105 valve construction for controlling the flow of water to and from a tank, comprising a float valve for controlling the flow of water to the tank, and a check valve for controlling the flow of water from the tank, said float valve 110 having a stem extending through said check valve and a water passage therethrough controlled by said check valve.

8. A combination float valve and check valve construction for controlling the flow of water to and from a tank, comprising a float 115 valve for controlling the flow to the tank, and a check valve for controlling the flow from the tank, said float valve comprising a tubular member having an annular seating 120 edge and having a water passage therethrough controlled by the check valve.

9. A combination float valve and check valve construction for controlling the flow of water to and from a tank, comprising a float 125 valve for controlling the flow to the tank, and a check valve for controlling the flow from the tank, said float valve comprising a tubular member having an annular seating edge and having a passage therethrough con- 130

trolled by said check valve, and an annular packing surrounding said tubular valve and exposed to the pressure of the water to hold it against said tubular valve.

5 10. A combination float valve and check valve construction for controlling the flow of water to and from a tank, comprising a float valve for controlling the flow to the tank, a check valve for controlling the flow 10 from the tank, said float valve having a passage controlled by said check valve, and a two-part casing for said valves, one of said casing parts having a passage for the inflow past the float valve, and the other having a 15 passage for the outflow past the check valve.

11. A combination float valve and check valve construction for controlling the flow of water to and from a tank, comprising a float valve for controlling the flow of water to the 20 tank, and a check valve for controlling the flow of water from the tank, the float valve having a passage therethrough controlled by said check valve, a packing surrounding said

float valve, and a two-part casing between the parts of which said packing is held. 25

12. A combination float valve and check valve construction for controlling the flow of water to and from a tank, comprising a float valve for controlling the flow to the tank, and a check valve for controlling the 30 flow from the tank, said float valve having a passage therethrough controlled by said check valve, a partition in which said float valve works and with which it has a watertight engagement, a valve seat for said float valve and a retaining ring for said valve seat of a smaller diameter than the opening 35 in said partition whereby it may be inserted through said partition in position.

In witness whereof, I have hereunto subscribed my name. 40
